UNITED STATES PATENT OFFICE.

GEORGE J. MURDOCK, OF NEWARK, NEW JERSEY.

STOCKING-SUPPORTER.

No. 838,618.

Specification of Letters Patent.

Patented Oct. 16, 1906.

Application filed November 7, 1905. Serial No. 286,188.

To all whom it may concern:

Be it known that I, GEORGE J. MURDOCK, a citizen of the United States, residing at Newark, in the county of Essex and State of New Jersey, have invented certain new and useful Improvements in Stocking-Supporters, of which the following is a specification.

My invention relates to improvements in stocking-supporters, and comprises means whereby the stocking is supported not by a garter or similar device worn around the leg, but by a device secured to the wearer's shoe.

My invention comprises a stocking-supporting strut, preferably flexible, adapted to be secured to the shoe and to support the stocking at some higher point.

Other features of my invention will be pointed out hereinafter and particularly specified in claims.

The objects of my invention are to improve the construction and operation of stocking-supporters; to avoid the many objections to garters and similar devices worn around the leg; to provide a stocking-supporter which shall be efficient, which shall conform perfectly to the movements of the wearer, and of which the wearer shall be practically unconscious while the device is in use, and to make the device simple, inexpensive, and reliable.

I will now proceed to describe my invention, with reference to the accompanying drawings, illustrating one form of the device, and will then point out the novel features in claims.

In the said drawings, Figure 1 shows a side view of the stocking-supporter in use. Fig. 2 is a side view of the device attached and is approximately full size. Fig. 3 shows an end view of the bottom clasp, and Fig. 4 shows a side view of such clasp.

It is well known that garters and similar stocking-supporters which are worn around the leg are injurious in their tendency, being apt to restrict the circulation. Moreover, they often cause much discomfort. Their clasps are objectionably thick, and at times they become unfastened or slip over the calf of the leg and fall down.

My improved stocking-supporter instead of being fastened about the leg of the wearer is not fastened to the leg at all, but to the shoe, and instead of being a suspension device it is a strut secured at or near its lower end to the shoe and secured at a higher point to the stocking. It is preferably formed of

piano-wire or other strong but flexible material and when properly adjusted to the shoe and to the stocking adapts itself perfectly to the movements of the wearer without sensibly resisting or restricting such movements, so that the wearer, in fact, becomes unconscious of the presence of the device. The device is provided with means whereby it may be attached to and detached from the shoe and stocking instantly.

In the form shown in the accompanying drawings my said stocking-supporter comprises a straight piece of flexible wire 1, provided at one end with means for attaching it to a shoe-upper and provided at the other end with means for attaching it to a stocking. The clasp for attaching the device to a shoe-upper is formed by merely bending the wire into a spiral coil of two or more turns. As shown particularly in Figs. 3 and 4, these turns preferably approach closely at the top and bottom of the coil and are spread at the sides of the coil in order to facilitate the attachment of the device to the shoe-upper. In applying the device to a shoe it is held nearly horizontally, which brings an open portion 2 of the bottom clasp 3 opposite the top edge of the shoe-upper, the distance between the coils at this point 2 being such that the edge of the shoe-upper may be inserted between the coils readily. This is done, and then the device is swung upward to a substantially vertical position, the clasp 3 turning upon the upper, so as to bring the latter between the coils at point 4, where said coils are normally close together. This portion of the clasp pinches the shoe-upper tightly, and thus holds the device 1 to the shoe firmly. The device for securing the stocking-supporter to the stocking is also simple, comprising a pin-point 5, surrounded by a guard-ring 6. As soon as the stocking-supporter has been secured to the shoe, as above described, and turned into the nearly-vertical position a portion of stocking near, but preferably slightly below, the point 5 is pressed through the ring 6 and over the point 5, the wire being sprung slightly to permit this. As soon as the wire is released it springs back straight, raising and stretching the stocking slightly. The guard-ring 6 at once holds the material of the stocking from passing too far down on the wire, prevents the stocking from becoming detached from the point 5, and prevents said point from sticking into the flesh of the wearer. I do not limit myself to

the use of these particular devices for fastening the stocking-supporter to the shoe and to the stocking; but the same are simple, easily made, efficient, and thoroughly satisfactory.

5 When the stocking-supporter is in use, it yields readily to the movements of the ankle, because of the flexibility of the wire of which it is composed, and does not restrict or impede in the least the movements of the ankle.

10 Neither does it restrict the circulation, and, in fact, the wearer will become unconscious of its presence almost instantly.

If desired, the upper portion of the stocking may be turned down over the ring 6, 15 forming a second covering for the point 5 and effectually preventing disengagement of the stocking from the device. It will be obvious that to disengage the stocking from the device when it is desired to do so is the work of 20 but an instant. It is unnecessary to remove the device from the shoe when taking off the latter.

What I claim is—

1. A stocking-supporter comprising a strut 25 flexible in all directions and provided with means for attaching it to the shoe and to the stocking of the wearer.

2. A stocking-supporter comprising a strut provided with means for engaging a stocking 30 and with a shoe-clasp comprising spiral coils adapted to grip a shoe-upper between them.

3. A stocking-supporter comprising a strut provided with means for engaging a stocking and with a shoe-clasp comprising coils which are relatively close together near the bottom 35 of the coil and are relatively far apart near one side of the coil.

4. A stocking-supporter comprising a strut provided with means for attachment to a shoe and with a stocking-fastening comprising 40 a point and a guard-ring surrounding the same.

5. A stocking-supporter comprising a piece of flexible wire having at one end spiral spring-coils adapted to grasp a shoe between 45 them, and at the other end having a stocking-fastening.

6. A stocking-supporter comprising a piece of flexible wire having at one end a point and a guard surrounding the same and having at 50 the other end a shoe-clasp.

7. A stocking-supporter comprising a single piece of flexible spring-wire bent at one end into a ring, the end of the wire forming a point projecting into the ring, the other end 55 of the wire bent to form a shoe-clasp.

In testimony whereof I affix my signature in the presence of two witnesses.

GEORGE J. MURDOCK.
